UNITED STATES PATENT OFFICE.

SEARS B. CONDIT, JR., OF BROOKLINE, MASSACHUSETTS, ASSIGNOR TO CONDIT ELECTRICAL MANUFACTURING COMPANY, OF SOUTH BOSTON, MASSACHUSETTS, A CORPORATION OF MASSACHUSETTS.

RENEWABLE ELECTRIC FUSE.

Application filed June 7, 1919. Serial No. 302,517.

To all whom it may concern:

Be it known that I, SEARS B. CONDIT, JR., a citizen of the United States, and resident of Brookline, in the county of Norfolk and State of Massachusetts, have invented an Improvement in Renewable Electric Fuses, of which the following is a specification.

My invention relates to a renewable electric fuse of the cartridge type and has for its object to provide a fuse of such type having a vent for the expulsion of heated gas formed upon the blowing of the fuse and the cooling of the gas during its expulsion whereby to prevent the discharge of a dangerous flame.

Certain features herein shown but not claimed are shown and claimed in my co-pending application Serial No. 302,516, filed June 7, 1919.

Fig. 1 is a side view, partly in section, of a renewable electric fuse embodying my invention.

Fig. 2 is an end view of the fuse with the end-plug in place.

Fig. 3 is a view of the inner face of the end-plug illustrating the gas passages therein.

Fig. 4 is a section along lines 4—4 of Fig. 3.

Fig. 5 is an end view of the fuse with the end-plug removed and illustrating the fuse-supporting plate and the fuse-receiving slot therein.

As here shown, my invention is applied to the renewable electric fuse having the enclosing tubular enclosing casing 10 of fibre or other suitable insulating material on the ends of which are permanently received the end-ferrules 11 which, at their end-portions, are interiorly-threaded as at 12. Each end ferrule is formed with the inwardly-extended flange 13 against which the end of the enclosing casing is designed to abut and which also serves as an abutment for the fuse-supporting plate.

The fuse-supporting plate comprises a disc 14, usually of copper, of slightly less diameter than the inner diameter of the end-ferrule whereby it may be removably received therein, and has a non-axial or eccentric slot 15 therethrough extended from the edge thereof beyond and above the center of the disc and terminates near the op-

posite edge of the disc. Said slot is adapted to be about midway between the center of the disc and the edge, as illustrated in Fig. 4, and is adapted to receive the fusible element.

The fusible element comprises the fuse strip of fusible material extended through the enclosing casing 10 and has its end-portion received in the fuse-receiving slot 15 and the extended end-portion is reflexed over the outer face of said fuse-supporting disc to which it is adapted to be clamped by the end-plug. The slot 15 is adapted to be of greater cross-section than that portion of the fuse received therein whereby it forms a gas vent for the casing.

The fuse clamping means comprises a clamping plate or end plug as the relatively thick disc 16, preferably of copper, having a threaded peripheral portion 17 whereby it is removably received in the end-ferrule, and the outer face thereof is provided with a slot 18 in which a screw-driver or other suitable tool is adapted to be received to remove said plug from or secure it to the fuse.

An axial opening 19 is extended through said plug and, in the outer face thereof, may be enlarged, as indicated at 20. A slot or gas passage 21 is formed in the inner face of said plug and extends from said opening 19 therein to the periphery of the plug. Said plug is adapted to be screwed against the reflexed end of the fuse strip to thereby secure it in firm electrical engagement with the fuse-supporting plate and consequently with the end-ferrule.

It will be noted that the fuse strip is relatively broad and the reflexed end thereof occupies the central portion of the space 22 between the fuse-supporting plate and the end plug whereby said space is roughly in the form of an annular ring closely bounded by said plate and plug with which the fuse-receiving slot 15 communicates. The axial opening 19 in the end-plug is closed by the reflexed end of the fuse strip and the slot 100 or passage 21 in the inner face of said plug communicates with said space 22 and said axial opening 19. By this arrangement the gas expelled from the interior of the fuse casing is caused to pass between the relatively closely-spaced and cold walls of the

plate 14 and end-plug 16 to said slot 21 and from said slot through the opening 19 in said plug. In its passage therethrough its direction of flow is altered many times and 5 the gas is brought intimately in contact with relatively cold heat-absorbing bodies whereby it is cooled and may be expelled from the fuse without flame.

It is obvious that modified arrangements 10 of my invention in which a tortuous path and cooling means for the outrushing gas may be provided without departing from the spirit of my invention.

I claim:—

- 15 1. A renewable electric fuse of the cartridge type comprising a tubular enclosing casing, an end ferrule received thereon having an end plate arranged over the end of the casing with an eccentric fuse and gas opening therethrough, a fuse strip extended through said opening having its end portion reflexed over the face of said plate, and a fuse clamping plate detachably received by said ferrule pressing the reflexed end of said 20 fuse strip against said end-plate, said clamping plate having an axial opening therethrough the inner end of which is closed by the reflexed end of said fuse strip and a gas passage in its inner face extending 25 from said opening toward the periphery of said plate to provide a vent passage from the fuse.
- 25 2. A renewable enclosed electric fuse of the cartridge type comprising a tubular enclosing casing, an internally screw-threaded end ferrule carried thereby having a fuse-receiving end-plate with an eccentric fuse-receiving and gas vent slot therethrough, a fuse strip extended through said slot having 30 its end-portion reflexed over the face of said end plate, and fuse clamping means comprising an externally screw-threaded plug removably threaded in said end ferrule and

engaging the reflexed end of said fuse strip and having an axial opening therethrough and a gas passage in its inner face extended from said opening toward its periphery. 45

3. A renewable electric fuse of the cartridge type comprising an enclosing casing, an end-ferrule received thereon, fuse-supporting means associated with said end-ferrule having an eccentric fuse-receiving slot therein, said slot also serving as a gas vent for the casing, a fusible element received in said casing having an end thereof 50 extended through said slot and reflexed, an end-plug removably threaded in said end-ferrule engageable with the reflexed end of said fusible element to clamp it to said fuse-supporting means, said end-plug having an axial opening therethrough and a passage communicating with said opening extended to the periphery of said plug and communicating with the space between said fuse supporting means and plug, whereby a tortuous 55 passage is provided for the expulsion of gas from the fuse.

4. A renewable electric fuse of the cartridge type comprising a tubular enclosing casing, end ferrules carried thereby, end-plates loosely received in said end ferrules having eccentric fuse-receiving slots therethrough, a fuse strip extended through said casing and the slots in said plates and the ends reflexed over the outer faces of said 70 plates, and plugs removably received in the outer ends of said ferrules engaging the reflexed ends of said fuse strip, said plugs having axial openings therethrough with slots in their inner faces extending from said axial openings to their peripheries to provide gas vents for the fuse. 75

In testimony whereof, I have signed my name to this specification.

SEARS B. CONDIT, JR.
